PHOTOGRAPH RECORD BOOK

Albert G. De Vry, Chicago, Ill.

Application March 4, 1950, Serial No. 8,330

Term of patent 14 years

(Cl. D6—2)

To all whom it may concern:

Be it known that I, Albert G. De Vry, a citizen of the United States, residing at Chicago, in the county of Cook and State of Illinois, have invented a new, original, and ornamental Design for a Photo Record Book, of which the following is a specification, reference being had to the accompanying drawing forming a part thereof, in which:

The single figure of the application is a perspective view showing the front cover and back of a photo record book embodying my new design.

I claim:

The ornamental design for a photo record book, substantially as shown.

ALBERT G. DE VRY.
